ANTISLURRING DEVICE

Oscar Charles Roesen, Brooklyn, N. Y., assignor
to Wood Newspaper Machinery Corporation,
New York, N. Y., a corporation of Virginia

Application December 8, 1928, Serial No. 324,593

2 Claims. (Cl. 101—225)

This invention relates to a device for preventing the slurring of the web as it passes over the impression cylinder and into contact with the plate cylinder. This is the principal object of the invention and it is carried out in a form in which the web is diverted from a straight path to the impression cylinder and caused to wrap around the impression cylinder through a considerable arc before it comes into the bite between the printing and impression cylinders.

Reference is to be had to the accompanying drawing in which

Fig. 1 is an end view of printing couples in a press showing a preferred embodiment of this invention applied thereto; and

Fig. 2 is a side view of the same;

In the form shown the slurring is prevented by bringing the web W, preferably over a guide roll 10. A set of feed tapes 20 are arranged to pass around three rolls 21 and 22 pressing against the impression cylinder. In this case the roll 22 is located on an arm 23, pulled back by a spring 24, so as to keep the feed tapes 20 under tension all the time and insure the application of the web W to the surface of the impression cylinder under some degree of pressure due to the feed tapes. These feed tapes are operated through a shaft 25 which has a pinion 26 meshing with a gear 27 on the impression cylinder. Therefore these tapes are positively driven from the press at web speed and force the web directly against the impression cylinder where it has a chance to remain pressed against that surface for approximately a quarter of a revolution before it comes into the bite of the impression cylinder 14 and the plate cylinder 15.

After the imprint on one side, of course, the web is perfected in the usual way by passing

over idlers 18 and through a second printing couple.

The web is held down against the surface of the impression cylinder positively at some distance from the bite between the two cylinders of the couple. This prevents vibration of the web and any tendency for undulation of the same and insures that the web at the instant of printing shall pass through the couple smoothly and in firm contact with the impression cylinder.

The mechanism for accomplishing this result is very simple and its drive is also reduced to its lowest terms. By this construction, without any material expense for installation or repairs, the product is very greatly improved.

Although I have illustrated and described only one form of the invention I am aware of the fact that other modifications can be made therein by any person skilled in the art without departing from the scope of the invention as expressed in the claims. Therefore, I do not wish to be limited to the mechanism shown but what I do claim is:—

1. The combination with a printing couple, of feed tapes engaging the impression cylinder and holding the web thereagainst, means for running said tapes at the speed of the surface of the impression cylinder, and yielding means for holding said tapes taut.

2. The combination with a printing couple, of a movable member in engagement with the web on the impression cylinder in advance of the point with which the impression cylinder comes into contact with the plate cylinder, and yielding means for moving a portion of said member away from the impression cylinder in a direction to apply a yielding tension to the web.

OSCAR CHARLES ROESEN.
